Jac. B. Hartman Inventor;

UNITED STATES PATENT OFFICE.

JACOB B. HARTMAN, OF WOOSTER, OHIO.

REFRIGERATOR.

SPECIFICATION forming part of Letters Patent No. 289,832, dated December 11, 1883.

Application filed March 8, 1883. (No model.)

To all whom it may concern:

Be it known that I, JACOB B. HARTMAN, of Wooster, in the county of Wayne and State of Ohio, have invented a new and useful Improvement in Refrigerators, of which the following 5 is a specification.

My invention relates to certain improvements in the construction and arrangement of refrigerator-buildings.

10 Refrigerators having some of the features described in connection with my invention have been heretofore used.

The object of my invention is to provide a simpler and more effective wall, and at the 15 same time a better method of ventilating the refrigerator than heretofore used.

My invention consists, first, in the use of a refrigerator-wall constructed with dead-air chambers, which have no connection whatever 20 with the interior of the refrigerator, or with the ventilating system thereof, or with each other, each dead-air chamber being separate and entirely surrounded by continuous sheathing of asbestos or other suitable material to 25 resist heat, and the number of such dead-air chambers being proportioned to the degree of heat-resistance required in any particular case. Heretofore air-chambers similarly constructed have been made to communicate with 30 the interior of the refrigerator and with each other, and also to form a means of ventilating the same. This method is objectionable because the ice is thereby more rapidly exhausted by means of the draft upon it, and by using 35 it to cool the air of the air-spaces; and, further, by this communication the interior cooling-chamber is at the same time brought into closer contact with the external air. This defect I overcome by the use of absolutely-dead-air 40 chambers lined, severally, with suitable heat-resisting material and entirely disconnected with the ventilating system.

My invention consists, secondly, in an improved device for ventilating the cooling-room. This I accomplish by the use of ventilating pipes or flues wholly disconnected with the dead-air chambers within the wall. These pipes are open at both ends, and extend vertically from the bottom to the top of the refrigerator, and in their passage intersect pipes leading from the cooling-room at the top of the refrigerator, so that the air-current which

naturally and constantly arises in the external ventilating pipes in passing over the mouths of the pipes leading from the cooling-room cause a suction thereupon after the manner of a siphon, which extracts warmth and dampness from the cooling-room without causing a draft directly upon the ice, or in any manner affecting the air within the dead-air 55 chambers.

My invention consists, lastly, in an improved external weather-casing for refrigerators exposed to weather or heat. This weather-casing is separated a few inches from the refrigerator-wall, and united at the top in the form of a roof with a ventilator in such a manner as to form an open continuous passage for air from the bottom of the weather-casing to the 60 ventilator at the top. The inner surface of 65 this external weather-casing, including the roof, is lined throughout with asbestos sheathing or other non-heat-conducting sheet lining. The open-air passage has no direct connection with the ice-chamber. I do not claim any 70 part of this external weather-casing, except the arrangement of internal non-heat-conducting linings and of a continuous air-passage disconnected from the interior, as above specified.

Referring to the drawings, in which similar letters of reference indicate like parts, Figure 1 is a vertical section of my refrigerator cut through opposite ventilating-flues in the sides and top. Fig. 2 is a horizontal section of the 75 same. Fig. 3 is a front elevation of a door of the same.

R, Figs. 1 and 2, is the refrigerating-chamber, in which is situate, near the top, an ice-receptacle, I, from which a duct, t, conducts 80 the ice-water into a reservoir, G, which empties externally through a pipe, t', by the spigot s.

A, A' are the two segments of an open hollow-wall which entirely surrounds the ice-chamber R. These segments are united and 85 form the dead-air chambers C, C.

D, D' are opposite ventilating-flues, which open externally at o, o', and pass up through the hollow wall and top, where they intersect 90 and pass over the openings E, E' from the ceiling of the ice-chamber, and afterward terminate in a common orifice, o", which may be closed by the valve i.

a a' are sheet linings of asbestos sheathing or other non-heat-conducting material adjacent to the open hollow of the wall.

X is the external weather-casing, with internal non-heat-conducting sheet lining *a''*, of asbestos sheathing or other suitable material continuous with the roof Z to the ventilator V. *y y'* are open air-passages between the weather-casing and refrigerator-wall.

10 L, Figs. 2, 3, is a door into the ice-chamber, having flanges F F', overlapping the margin of the entrance, and forming an angle or corner to receive the elastic cushion-strip P P, attached to the margin, so that when the door 15 is shut the crevice will be air-tight. The arrows show the direction of the air-currents.

What I claim as new, and desire to secure by Letters Patent, is—

1. In a refrigerator, the combination, with an open hollow wall constructed with dead-air chambers severally lined with sheathing of asbestos or other suitable material, the dead-air chambers having no communication with the interior of the refrigerator, or with the ventilators thereof or with each other, of 25 ventilating-pipes D D', in connection with intersecting siphonal pipes E E', when the ven-

tilating-pipes have no communication with the dead-air chambers, substantially as and for the purpose specified.

2. In a refrigerator, the combination, with an open hollow wall forming dead-air chambers lined with asbestos sheathing or other suitable non-heat-conducting lining surrounding an ice-chamber, the dead-air chambers 35 having no communication with the ice-chambers, or with the ventilators thereof or with each other, of an external weather-casing open below and separated from the wall by a continuous air-space, and united at the top to 40 form a roof with a ventilator, where such external casing and roof are lined upon their inner surface with asbestos sheathing or other suitable non-heat-conducting sheet lining, and said air space is disconnected with direct air-passages from the ice-chamber, substantially 45 as set forth.

In testimony whereof I hereunto set my hand and seal this 30th day of January, A. D. 1883.

JACOB B. HARTMAN. [L. S.]
